(57) **CLAIM**

The ornamental design for a can compactor and bin, as shown and described.

DESCRIPTION

FIG. 1 is a right side, top and front perspective view of the can compactor and bin showing my new design and showing the bin disengaged from the compactor;

FIG. 2 is right side, top and front perspective view of the can compactor and bin showing my new design and showing the bin engaged with the compactor;

FIG. 3 is a front elevational view thereof;

FIG. 4 is a rear elevational view thereof;

FIG. 5 is a right side elevational view thereof;

FIG. 6 is a top plan view thereof; and,

FIG. 7 is a bottom plan view thereof.

The bin is shown broken away to indicate indeterminate length.
